METHOD OF MAKING GARMENT-STAYS.

1,123,822.

Specification of Letters Patent.

Patented Jan. 5, 1915.

Application filed July 17, 1912, Serial No. 710,008. Renewed October 21, 1914. Serial No. 867,896.

To all whom it may concern:

Be it known that I, FRANK L. O. WADSWORTH, a resident of Sewickley, in the county of Allegheny and State of Pennsylvania, have invented a new and useful Improvement in Methods of Making Garment-Stays, of which the following is a specification.

This invention relates to the manufacture of wire garment stays, and particularly to that form of stay which is made up of wire bent back and forth alternately in opposite directions to form two series of oppositely disposed loops or eyes lying along the edges of the stay and united by a series of intermediate transverse portions or crossings lying at nearly right angles to the length of the stay. In such stays the resistance to flatwise bending is due almost entirely to the torsional stiffness of the transverse portions or crossings, while the resistance to edgewise bending is due almost entirely to the lateral stiffness, or the resistance to bending of those portions of the wire which form the edge loops. Usually such stays are subjected to much more severe bending stresses in a flatwise direction than they are in an edgewise direction. It is, therefore, particularly important to form the stays in such a manner that the torsional stiffness and resiliency of the crossing portions of the wire may be as great as possible.

The particular objects of the invention are to provide a method of forming stays of the character described whereby such stays are not only rendered stiffer in one flatwise direction than in the other but also possess an increased resiliency and increased ability to withstand short bends and avoid taking permanent bends or sets, as compared with such stays as heretofore constructed.

It is well known that when wire is subjected to twisting stresses sufficient to impart a permanent torsional set thereto, the torsional resistance of the wire against a further twist in the same direction is greatly increased and the elastic limit or resiliency of the wire is likewise increased. I take advantage of this characteristic of wire and form the stays in a manner that each crossing or transverse portion of the wire body is twisted during the formation of the stay to a sufficient degree to impart a permanent set thereto,—the twisting operation being so

performed that in the finished stay all of 55 the crossings are twisted or set in the same direction. The result is a stay which is considerably stiffer against flatwise bending in both directions than a similar stay having no twist in the crossings; which, further, is 60 stiffer against bending in the flatwise direction which produces a further twist in the crossings or transverse portions in the same direction in which they were already twisted, than against bending in the opposite flatwise direction; and which, finally, is considerably more elastic and resilient and, therefore, capable of being subjected to shorter bends without permanent distortion than it otherwise would be. As a consequence, a stay manufactured according to this method can be made of smaller and lighter wire than when made according to the old method, without rendering the stay unduly flexible, as well as possessing other 75 advantages which will be readily appreciated by those skilled in the art.

In the accompanying drawings, Figures 1, 2 and 3 illustrate in plan, side and end views respectively one form of stay and my 80 improved method of making same; and Figs. 4 and 5 illustrate a mechanism which I have devised for the more convenient carrying out of this improved method.

The stay shown in Figs. 1, 2 and 3 is made 85 up of wire of suitable size bent back and forth alternately in opposite directions to form two series of oppositely disposed loops or eyes 1, lying along the two edges of the stay body and connected by transverse portions or crossings 2. The eyes or loops are preferably overlapped, so that when viewed edgewise, as in Fig. 2, they present a "shingled" appearance; but they may also be formed otherwise if desired. In making 90 this form of stay, or in making any corresponding form of stay, in accordance with my present invention each loop or eye of the stay is first formed at a very pronounced angle to the plane of the stay, (as shown at 100 3) and is then tilted or twisted as a whole so as to bring it to the general plane of the stay. This can be done by hand, each loop or eye being first formed out of the plane of the stay by the aid of round-nosed pliers, indicated at 4 in Fig. 3, and then turned down to the required position of parallelism with the previously formed loops either 105

2
by the aid of the same pliers or by grasping the end of the loop with a pair of flat nosed pliers. This operation imparts to each crossing portion 2 of the wire a twist or torsional set, the amount of which depends upon the angle at which the loop is first formed to the plane of the finished stay. The loops or eyes of the opposite edges are, of course, all rotated or twisted in the same direction so that the twist and the permanent set imparted thereby to the crossings is in the same direction in each crossing of the finished stay—as indicated by the arrows of Figs. 1 and 2.

15 In the second or twisting step of the operation it is possible to rotate each loop or eye beyond the plane of its final position, as shown at *a*, Fig. 2, so as to provide for recoil when the loop is released. If the 20 angle of twist is properly controlled the recoil will be just sufficient to bring the twisted loop into a permanent set position parallel to the previously formed loops and thus produce a stay which will be perfectly 25 flat, that is, which has no tendency to twist or curl sidewise as it will when produced in the usual way.

While my improved method may, as above 30 described, be carried out by hand, I prefer to employ a suitable mechanism for this purpose, such for example, as that illustrated in Figs. 4 and 5. In this mechanism, the wire is fed at an angle to the plane of the formed stay, and as illustrated in the 35 drawings, is fed substantially normal to the plane of the stay by suitable guide rollers 5, 5^a. The unformed portion of the wire is caught alternately by the reciprocating bending members 6 and 6^a which come in 40 endwise at an oblique angle and alternately from opposite sides, and which are provided on their ends with suitable notches or lips 7 for receiving the unformed part of the wire, carrying it across the width of the stay being 45 formed and bending the same into a loop, standing substantially normal to the plane of the stay. These bending members may be reciprocated by any suitable mechanism, such for example as the oscillating 50 levers 8 and 8^a. During this movement the previously formed portion of the stay is held clamped between an anvil or forming block 9 and vertically reciprocating pin blocks 10, 10^a which are provided with pins 55 11 and 11^a, which engage and hold the previously formed loop or eye. We will assume that the pin block 10^a is elevated and the pin block 10 is depressed to clamp the formed portion of the wire against the anvil 9, with the unformed part of the wire caught by the bending member 6. This member is then advanced in a straight line and carries the unformed part of the wire across the width of the stay to form a loop. 60 65 When fully advanced, the member 6 is given

a partial rotation in the direction of the arrow 12, Fig. 4, either by hand or by any suitable mechanism and thereby brings the loop portion last formed into the plane of the previously formed loop and in position 70 under the forward pin in the elevated pin block 10^a. Said bender is then retracted and returned to its normal position and the pin block 10^a descends and catches the newly formed loop on its forward pin 11^a. Immediately thereafter the pin block 11 rises and the pin block 10^a is moved backward a distance equal to one-half the interval between the adjacent eyes so as to bring the depressed pins 11^a opposite the position previously occupied by the depressed pins 11 (see Fig. 5). The opposite bending member 6^a now advances, catches the unformed part of the wire and bends it back toward the opposite edge of the stay and forms 85 another loop. Said loop will be standing substantially normal to the planes of the previously formed loops. The member 6^a is then rotated in the direction of the arrow 12^a, Fig. 4, thereby bringing this newly 90 formed loop portion into the plane of the previously formed loops and in position under the forward pin 11 of pin block 10, when said member 6^a is retracted and thrown back to its former position, after 95 which the pin block 10 is lowered and catches the newly formed loop behind its forward pin 11, when the foregoing operations are repeated.

The bending members 6 and 6^a can be 100 rotated as above described by any suitable mechanism, the drawings merely showing diagrammatically such rotating mechanism as consisting of sleeve gears 14 in which the bending fingers 6 are splined so they 105 can slide therein but must be rotated therewith and which gears 14 mesh with other gears 15 which will be intermittently rotated or oscillated back and forth by any suitable mechanism.

The principle of manufacture described 110 can be applied to a stay for any desired form of loops or eyes and having any desired form of cross section, that is to say, the loops or eyes may be pear-shaped, U-shaped or of any other shape and they may be brought entirely into the plane of the stay to form a perfectly flat stay, or may be allowed to overlap and remain slightly tilted out of the plane of the stay, as shown 115 in Figs. 1, 2, 3 and 5.

In every case, the effect of tilting each 120 loop or eye from the original position in which it is formed toward the plane of the stay is to impart a very considerable twist or torsional set to the transverse or crossing portion 2 of the stay. Consequently, these transverse or crossing portions will resist a tendency to twist or rotate them farther 125 in the direction in which they are already 130

twisted, more strongly than they resist a tendency to twist or rotate them in the opposite direction. The twists or torsional sets in all of the crossings, viewing the stay 5 as a whole, run in the same direction. Consequently, the stay is much stiffer in one flat-wise direction than it is in the other, so that by properly placing it in a garment, such as a corset, it is enabled to resist to a maximum 10 the stresses to which such stays are normally subjected in use, while leaving it very flexible in the opposite direction. This initial twist or torsional set has the further effect of increasing the elasticity or resiliency 15 of the wire in both directions and, as a consequence, the stay can be bent to very short radii of curvature without taking a permanent set or bend, and sharply recovers its original or normal form. Hence, 20 the garment will retain its form much more effectively than with stays similarly constructed but having no initial twist or torsional set.

I am aware that it is not new to make a stay 25 having the crossing portions twisted and given an initial set, but in the methods of manufacture heretofore employed, such twist has been imparted to the stay during the bending of the loops. My method differs 30 from previous methods in that the bending operations and twisting operations are not simultaneous, but are successive, so that the amount of twist is entirely independent of the nature of the bending operation. 35

What I claim is:—

1. The method of forming garment stays, consisting in bending wire alternately back and forth to form a series of oppositely dis-

posed loops or eyes, in a manner to form 40 the plane of each loop or eye at an angle to the plane of the stay as a whole, and twisting or tilting each loop or eye as formed to bring the plane nearer to the plane of the stay as a whole. 45

2. The method of forming garment stays, consisting in bending wire alternately back and forth to form two series of oppositely disposed loops or eyes, in a manner to form 50 the plane of each loop or eye in a plane at an angle to the plane of the stay as a whole, and then rotating or tilting said loops and bringing the same into the plane of the stay as a whole, all said loops or eyes being rotated in the same direction. 55

3. The method of forming wire garment stays, consisting in bending wire back and forth alternately in opposite directions and forming oppositely disposed loops or eyes, and then twisting the transverse or crossing 60 portions of the stay to bring the planes of the loops or eyes into the general plane of the stay. 65

4. The method of forming garment stays consisting in bending wire alternately back 65 and forth to form a series of oppositely disposed loops or eyes, in a manner to form each successive loop or eye with its plane at an angle to that of the preceding loop or eye, and tilting said loops or eyes to bring 70 the same into the general plane of the stay as a whole.

In testimony whereof, I have hereunto set my hand.

FRANK L. O. WADSWORTH.
